Primary Examiner—Joel Sincavage*Attorney, Agent, or Firm*—Merchant, Gould, Smith, Edell, Welter & Schmidt, P.A.**[57] CLAIM**

The ornamental design for a tool battery charger, as shown and described.

DESCRIPTION

FIG. 1 is a front top and right side perspective view of a first embodiment of a power tool battery charger;

FIG. 2 is a bottom rear and left side perspective view of the battery charger shown in FIG. 1;

FIG. 3 is right elevational view the battery charger shown in FIG. 1;

FIG. 4 is a left elevational view of the battery charger shown in FIG. 1;

FIG. 5 is a rear elevational view of the battery charger shown in FIG. 1;

FIG. 6 is a front elevational view of the battery charger shown in FIG. 1;

FIG. 7 is a top plan view of the battery charger shown in FIG. 1;

FIG. 8 is a bottom plan view of the battery charger shown in FIG. 1;

FIG. 9 is a front top and left side perspective view of a second embodiment of a power tool battery charger;

FIG. 10 is a rear bottom and left side perspective view of the battery charger shown in FIG. 9;

FIG. 11 is right elevational view of the battery charger shown in FIG. 9;

FIG. 12 is a left elevational view of the battery charger shown in FIG. 9;

FIG. 13 is a rear elevational view of the battery charger shown in FIG. 9;

FIG. 14 is a front elevational view of the battery charger shown in FIG. 9;

FIG. 15 is a top plan view of the battery charger shown in FIG. 9; and,

FIG. 16 is a bottom plan view of the battery charger shown in FIG. 9.
